UNITED STATES PATENT OFFICE.

ERICH H. LICHTENBERG AND GEORGE EVANS WEBB, OF MILWAUKEE, WISCONSIN, AS
SIGNORS TO KOEHRING COMPANY, OF MILWAUKEE, WISCONSIN.

WATER-INTRODUCING MEANS FOR CONCRETE MIXERS.

Application filed May 26, 1925. Serial No. 33,063.

Highway construction in the majority of the States in this country is being carefully supervised in respect especially to the regulations which govern the operation of mixing machines used for mixing the concrete employed for building concrete roads and highways.

For instance, the length of the period of the mixing of the concrete in the mixing machine or paver, as it is called, is definitely controlled usually by a batch meter. This batch meter is required to be used so as to insure that the concrete will be mixed a period of not less than one minute, usually, and for a mixing period of from a minute to a minute and a half in most States.

The requirements governing the mixture of the aggregates heretofore have had to do primarily with the solid aggregates and have not dealt with the time of mixing of the said aggregates with the water. Certain States of the Union are now requiring, however, that the period of the mixing of the solid aggregates and water commence when all of the aggregates, including the water, have been received in the mixing drum of the paver. In other words, considering the commencement of the mixing period in the mixing drum as the "zero hour" of said mixing period, from which shall begin the timing action of the batch meter or any equivalent means employed for the purpose, it is necessary that the water be in the mixing drum along with the solid aggregates at this "zero hour".

The foregoing situation makes for difficulty in regard to concrete paving machines already in the field, and even those at present being manufactured, because of the present method of coordination of the operation of the skip which supplies the solid aggregates to the drum and the water supply means employed to charge the drum with the necessary water for the mixing of a batch of said aggregates. This is due to the fact that the time required to charge the solid aggregates in the drum has heretofore been less than the time required to enable a measured quantity of water to pass from the usual measuring water tank to the drum. Obviously, this condition interferes with the efficiency of the mixing machine if it is required that the water be in the drum before

or at the time of the "zero hour" of the mixing period. This loss of time in the use of the machine is caused by the fact that the mixing period cannot start until fifteen or twenty seconds, more or less but stated approximately, after the solid aggregates are in the mixing drum. When it is considered that hundreds of batches of concrete are turned out by a large paving machine each day, this loss of time on each batch will run up to hours in an entire day's work, and this represents a tangible loss of the efficiency of the machine.

In the Letters Patent of one of us, namely No. 1,523,548, issued January 20, 1925, the above problem is dealt with by the provision of special mechanical forcing means, preferably a piston pump, by which to insure that the water required for a batch of concrete may be accelerated in its movement so as to get it into the mixing drum in much less time than is required under ordinary practice with the usual machine.

The object of the present invention has been to devise improved means for accomplishing the result herein outlined; said means being more simplified than that proposed in the said Letters Patent, and involving the use of air pressure forcing means instead of a mechanical force acting directly upon the water in the measuring tank.

In the carrying out of the means and method of the invention herein, we have devised novel provisions for providing a compressed air supply, and we have evolved other novel provisions whereby this compressed air supply may be used where different measured quantities of water are required to be drawn from the measuring tank.

To the above ends, according to this invention we employ the measuring tank provision substantially like that now used on large concrete pavers, except that we combine therewith certain novel air valve means. This air valve means is such that as the water from the main line supply is caused to pass into the measuring tank, such water acts as an air compressor to compress a sufficient supply of air previously automatically admitted to the tank, which air later on acts as a propelling means for ejecting the water with piston force from the tank when the

connections between the tank and the mixing drum are opened to permit the water to flow into the latter.

The foregoing represents what we believe is a broadly new idea in this art, and we do not therefore wish to be restricted to the specific details of the instrumentalities hereinafter presented for accomplishing the desired result.

10 Supplementing the foregoing, there may be employed a special air compressor which may also function as an air reservoir and which is adapted to act somewhat in the capacity of a "booster" for maintaining the 15 air pressure continuous during the discharge of the water to the mixer.

The means just referred to is in the nature of a mechanical compressor or pump, and is intended to be operated by the loading skip as the latter is raised to charge the 20 mixing drum with the solid aggregates. The said compression pump may be adapted to operate its piston means with a variable stroke in order to effect the formation 25 of a certain amount of compressed air for the purposes of the invention.

In the accompanying drawings:

Figure 1 is a side elevation of a mixing machine equipped with the invention; 30 Figure 2 is a view similar to Figure 1, broken away in regard to the mixing drum and loading skip provisions, but showing, however, a modified construction wherein a mechanical air compressing device is available;

Figure 3 is a sectional view of the air valve;

Figure 4 is a top plan view of the water and air tanks and connections;

Figure 5 is a sectional view of the water separator used with this apparatus; and

Figure 6 is a side view showing a modified form of the invention comprising a single combination water and air tank.

Referring to Figure 1, A denotes the framework of a mixing machine of the concrete paver type, the same being such as has endless treads or the like by which the machine is rendered portable, which treads however, are omitted because they are immaterial to the proper disclosure of this invention.

The mixing drum is designated B and the loading skip C. These various parts just referred to may be largely of conventional construction. Above the drum B, or somewhere adjacent thereto, is located the measuring tank 1. This tank is adapted to retain the water designed to the supplied to the drum B in a measured quantity for each batch of aggregates that are mixed in said drum. The measuring means for the tank 1 is not a feature of this invention, for any conventional means of this sort known to those versed in the art to date may be

used. An example of one such means, is that set forth in the Koehring Patent No. 1,145,922 issued August 10, 1925.

The tank 1 is provided with an automatic air valve 2 shown best in Figure 3. The said valve is suitably carried by the tank 1, being connected with the latter by the pipe 3 with which is coupled a water pressure gage 4. In a suitable position on the framework A, there is located an air tank 5 connected by a pipe 6 with the water measuring tank 1 at the top of the latter. On the pipe 6 there is provided the air pressure gage 7.

The air valve 2 located in the pipe line 80 between the tanks aforesaid, comprises a casing having an opening 2' at its upper end. In the casing is the valve member 2" having a suitable guide stem 3', said valve being adapted to close against the valve seat 8 as an incident to internal pressure of the tank 1.

Leading from the tank 1 to the mixing drum is a water outflow pipe 9 in the length of which is provided a three-way valve 90 means 10. This three-way valve may be of different constructions. It suffices for the purpose of this invention, however, to explain that in one position of the valve operating lever 11 the valve means 10 is maintained adjusted to permit water to flow from the main supply line 13 into the bottom portion of the measuring tank 1. In another position of said valve means 10, the water from the main supply line pipe 100 13 will be cut off, and the liquid contents of the tank 1 will be free to pass through the pipe 9 into the mixing drum B. It should be noted that the valve means 10 is so designed that when the supply line 13 is in 105 communication with and supplying water to the tank 1, said supply line is cut off from the outflow pipe 9 so that no water may pass through the latter.

The function of the valve means 10, 110 therefore, is to permit water to pass from the supply line 13 to the tank 1 cutting off the flow from the tank 1 to the drum B; or by coordination to cut off the supply of the water from the tank 1 to the outflow 115 pipe 9 and establish communication between the pipe 13 and said tank for replenishing the measured quantity of water to be received in said tank and later dispensed to the mixing drum when the latter 120 is charged with solid aggregates.

Attention is called to the fact that there may be provided a water supply pipe 13^a leading from the main supply line pipe connection 13 to the bottom of the air tank 5 125 so that water may be introduced into said air tank 5, for reasons hereinafter set forth. A three-way valve 15 at the bottom portion of the tank 5 controls the admission of water from pipe 13^a into the tank 5; in one posi- 130

tion being adapted to open the tank to the water supply pipe, in another position to close such communication, and in a third position to open the tank 5 to the discharge or outlet pipe 16 so that while the tank is closed off from the pipes 13 or 13^a, as the case may be, the water in the tank may be permitted to drain off therefrom. Under these conditions, it is possible to control accurately the amount of water in the tank 5, and if desired the water gage 5' may be provided at one side of the tank 5 to facilitate the determination of the quantity of water in said tank.

15 In order to operate the valve actuating lever 11, there is provided a hand lever 17 pivoted to the frame A at 18 and connected by a rod 19 with the free end of the said lever. The rod 19 extends a sufficient distance to project from the frame A into the path of a projection 20 on the skip C, so that as the skip C rises to discharge a batch of solid aggregates into the drum B, the lever 11 will be tripped at a predetermined moment to open the valve means 10 to establish communication between the measuring tank 1 and the outflow pipe 9.

More specifically, in the movement of the skip the projection 20 strikes the shoulder 30 19', imparting a longitudinal movement to the rod 19, during which the downwardly bent extremity 19" rides on the roller 19^a carried by the frame A. This shifts the movable section of the rod 19 upwardly and 35 frees the shoulder 19' from the projection 20 in the continued movement of the skip upwardly.

40 The outflow pipe 9 is a large diameter pipe so that the water in the tank 1 may flow freely and quickly to the drum B. The water outflow pipe 9, the valve means 10, and the pipe 9' connecting the means 10 with the tank 1, are all larger than customarily provided and sharp turns in the 45 lengths of these pipes and valve connections are avoided so that the water may pass freely under pressure from the measuring tank 1 to the drum B.

46 The operation of the invention is as follows:

The mixing drum B is normally rotated in the operation of the machine. It will be assumed that the tank 1 is empty, except, of course air is contained therein. The operator moves the water supply valve 10 to permit flow of the water from the pipe 13 to the tank 1, the water being under considerable pressure varying usually from thirty pounds to one hundred and fifty 55 pounds, depending upon the sources from which it is taken. As the water passes into the tank 1 the air in this form of the apparatus is pushed out through the valve 2, pipe 6 and into the storage reservoir 5 in which 60 it is compressed. When the tank is filled or the water reaches the valve member 2', its pressure forces said member to close thereby cutting off passage of the water into pipe 6 and the tank 5. The measured quantity of water for the particular mix is now 70 ready for use.

75 The operator starts the skip, previously loaded with the aggregates, upwardly. As the rod 19 is shifted by the skip the valve 10 is also moved to cut off the water pressure from the supply line and the pipe 9 opened. Immediately the water in tank 1 is charged into the mixer drum B under the action of the compressed air in the tank 5 through the pipe 9, the emptying of the water being very 80 greatly accelerated. The skip goes down after the discharge of its contents. The spring 21 acts to hold the valve means 10 in either of its operative positions and assists in quickly moving the valve means through the lever 11 from one of its operative positions to the other. The operator now throws the valve means 10 to close the connection from the tank 1 to the drum B and to open 85 communication between the main supply line pipe 13 and the tank 1.

90 Under ordinary conditions, the air tank 5 will be of the capacity to show thirty or thirty-five pounds pressure when the pressure in the water line is one hundred and fifty pounds and the minimum amount of water measured is being drawn off and refilled into the measuring tank 1 in the use of the machine.

95 It is obvious that inasmuch as variable quantities of water are measured by the tank 1, some means for raising the pressure of the air for minimum quantities of water handled by the tank 1, as compared with the air pressure used in handling the larger measured quantities of water, will be required. The foregoing is accomplished by providing a means for changing the volume of air capacity of the tank 5. The most simple means for doing this is to introduce into the tank 5 at its bottom a greater or less quantity of water through the operation of the valve 15, either to admit the water to the tank or to drain it as desired. The water being an 100 incompressible liquid provides virtually the equivalent of a rigid partition within the tank 5 to limit the receiving capacity of said tank to accommodate for different amounts of water which are handled by tank 1. The operator is able to read the desired air pressure on the gage 7 as he admits the water 105 into the tank 5 and said pressure must never exceed the water pressure in the measuring tank 1 when the air valve member 2" closes.

110 The water pressure will be built up to the pressure in the supply line and may be as much as twice the air pressure. This is controlled by the means for controlling the volume or capacity of the air tank 5 in the manner before described. Under some conditions 115 the water pressure will be built up to the pressure in the supply line and may be as much as twice the air pressure. This is controlled by the means for controlling the volume or capacity of the air tank 5 in the manner before described. Under some conditions 120 the water pressure will be built up to the pressure in the supply line and may be as much as twice the air pressure. This is controlled by the means for controlling the volume or capacity of the air tank 5 in the manner before described. Under some conditions 125 the water pressure will be built up to the pressure in the supply line and may be as much as twice the air pressure. This is controlled by the means for controlling the volume or capacity of the air tank 5 in the manner before described. Under some conditions 130 the water pressure will be built up to the pressure in the supply line and may be as much as twice the air pressure. This is controlled by the means for controlling the volume or capacity of the air tank 5 in the manner before described.

tions, the water tank 1 may fill and close the air valve 2" with the air pressure gage 7 showing thirty-five pounds and the water pressure may have been slowly built up to one hundred and eighty pounds or even higher. This may happen where the water supply is insufficient so that the tank 1 fills very slowly.

Experiments have shown that little is gained in the use of the invention in employing air pressure in excess of thirty-five pounds with as much as a seventy pound water pressure in the water supply line pipe 13.

Figure 2 is a view illustrating a slightly modified adaptation of the invention in which we utilize, connected up with the water tank 1, means for compressing air in the tank 1, acting auxiliary to the action of the water that enters this tank. Thus there is provided a compression cylinder 22 connected by a pipe 23 in communication with the top portion of the tank 1, by direct connection with the pipe 3 or any other method desired.

In this compression cylinder 22 is a piston 24 having an actuating rod 25 adapted to be shifted through the adjustable lever arm 26 which is connected to one end of a cross shaft 26' journaled on the frame of the machine. The shaft 26' is provided with a second arm 26" having a roller 26^a at its outer extremity, which latter normally lies in the path of travel of a projection C' which is in the form of a channel having one side flange shorter than the other, as clearly shown in Figure 2. The lever arm 26" is limited in its movement by the stop member 27 and in the operation of the device as the skip C is moved upwardly the roller 26^a will pass into the channeled member C' which causes the actuating rod 25 to shift the piston 24 inwardly of the cylinder 22. In this form of the invention, which dispenses with the storage tank 5, the cylinder 22 performs the dual function of acting as the air reservoir and as an air compressor. That is to say, the inflow of the water into tank 1 compresses the air in the cylinder 22, and as the skip later moves upwardly and the tank 1 is vented to discharge the water the piston 24 moving inwardly performs a compressing function maintaining the maximum pressure continuous during the outflow of the water.

As the skip returns to its lowermost or grade position the piston 24 is shifted outwardly by the channel member C' which latter becomes disengaged from the lever arm 26" when said arm has reached its limit of movement, as prescribed by the stop 27.

It should be understood that the foregoing construction is merely an exemplification of one type of means for accomplishing the function of supplying auxiliary air

but we do not wish to be confined to the form of mechanism which is herein illustrated.

The manual lever 17 enables the operator to actuate the valve means 10 manually for controlling the closing off of the communication between the supply pipe 13 and the tank 1, or to permit the actuation of the valve means 10 in order to supply an additional quantity of water to the drum B if the original measured quantity is not sufficient for the mixing operation. The lever 17 may be manipulated by the operator who consults the gages 7 and 4, also the water gage 5' of the tank 5.

It is understood that there may be employed in conjunction with the water control means of this invention a batch meter for controlling and indicating the time of the mixing period as set forth in Letters Patent No. 1,523,548 before referred to.

Figures 1 and 5 illustrate a form of separator which may be used in connection with the invention, though it is not absolutely necessary. This separator is designated as 28, and is preferably located according to the construction of Figure 1, above the automatic valve 2. Said separator acts as a device to prevent the water, or some vapor-laden air from passing into the air tank or compartment. The separator is merely a hollow body having internal baffle plates 29 which act to interrupt and separate the moisture or water from the air, the moisture or water flowing back into the water tank when the air valve 2 opens. The opening of the air valve takes place the instant the water pressure is relieved by opening of the discharge valve means to supply water to the mixing drum.

In the construction of Figure 6 there is used a water and air tank in one, designated as 30. The water compartment space is shown at 31, and the air space at 32, the partition 33 separating the two. In this construction, the water space and the air space are connected by suitable pipe means corresponding with that previously described, the same leading from the side of the separator 28 instead of the top as in Figure 1.

The principle of the invention is substantially the same as before set forth. The water space 31 is connected with the air chamber 32 for supplying the latter with water to reduce its capacity by means of a pipe 34 having the three-way water control valve 35 which functions like the previously described valve which is located beneath the tank 5 and in communication with a water line.

It is to be understood, of course, that the air valve 2 is a form of check valve and will permit air to pass by, but not water. The instant the air in the tank 1 or water space 31 is totally expelled and the water attempts

to flow out, the check valve 2 will float up and close against its valve seat.

With this invention we have been able to cause an emptying of the tank 1, and passing of its water content to the mixer B so quickly that there is practically no time lost in getting the water into the mixer, which time is subsequent to that for charging the drum B with the solid aggregates. Moreover, the action of the valve means 11 may be timed to be tripped by the skip C to start the water into the mixer a little ahead of the said aggregates.

Having thus described our invention, what we claim as new and desire to secure by Letters Patent is:

1. In combination, a concrete mixer, comprising a mixing drum, a water tank for supplying water to said drum, a water line to supply water under pressure to said tank, the said mixing machine including a loading means for charging solid aggregates into the drum, and means operated by the last mentioned means for compressing air to act upon the water in the water tank for forcing the water from said tank into the mixing drum.

2. In combination, a mixing machine, a water tank for supplying water to be mixed with solid aggregates in the machine, solid aggregate charging means for the machine, and air compressing means controlled by the last mentioned means for accelerating the flow of water from the water tank to the mixing instrumentalities of the mixing machine for admixture with the solid aggregates operated on thereby.

3. The method of accelerating delivery of a liquid supply to concrete mixers which consists in forcing the liquid into a reservoir chamber, trapping the air displaced therefrom in a separate communicating chamber of restricted capacity to build up a predetermined pressure in the latter, interrupting communication between the chambers when the first mentioned has received its measured quantity, and finally venting the reservoir chamber to permit discharge of its contents under influence of the trapped air pressure.

4. In combination, a concrete mixing machine, comprising a mixing drum, water supply means for said mixing drum including a water tank and means operable by the mixing machine itself for causing compressed air to act on the water in the water tank for forcing back water to the mixing drum.

5. The method of supplying water to concrete mixers which comprises introducing water under pressure into a reservoir and trapping the air content thereof to build up an expulsion pressure head for said water, compressing said trapped air to effect an increase of said pressure head incident to

charging of aggregates into the mixer, and finally expelling the water into the mixer under the pressure head of the said trapped and compressed air.

6. In water supply means for concrete mixers, in combination, a water tank having a water inlet and a discharge line to the mixer, a water line to supply water under pressure to said tank, air receiving means, a valve intermediate the tank and air receiving means, and valve means to control passage of water to the tank from the supply line to compress the air previously in the tank in the air receiving means so that said air will act as a motive fluid to thereafter expel the water from the tank, and also to establish communication with the mixer discharge line.

7. In water supply means for concrete mixers, in combination, a water tank, a water line to supply water under pressure to said tank, air controlling means, and valve means to control passage of water to the tank from the supply line to compress the air previously in the tank in said air controlling means so that said air will act as a motive fluid to thereafter expel the water from the tank, and also to control the outflow of the water from the tank, a mixing drum to which the water in the tank may flow when expelled therefrom, and a mixer loading skip adapted to actuate the said valve means.

8. In water supply means for concrete mixers, in combination, a water tank, a water line to supply water under pressure to said tank, air controlling means including an automatic check valve, and valve means to control passage of water to the tank from the supply line to compress the air previously in the tank in said air controlling means so that said air will act as a motive fluid to thereafter expel the water from the tank, and also to control the outflow of the water from the tank.

9. In water supply means for concrete mixers, in combination, a water tank, a water line to supply water under pressure to said tank, valve means to control passage of water to the tank from the supply line to compress the air previously in the tank so that said air will act as a motive fluid to thereafter expel the water from the tank, also to control the outflow of the water from the tank, and an air tank into which the air in the water tank is forced and compressed when the water is admitted to the water tank, and means to vary the capacity of the air tank.

10. In water supply means for concrete mixers, in combination, a water tank, a water line to supply water under pressure to said tank, valve means to control passage of water to the tank from the supply line to compress the air previously in the tank so that said air will act as a motive fluid to thereafter expel the water from the tank, also to control

- the outflow of the water from the tank, an air tank into which the air in the water tank is forced and compressed when the water is admitted to the water tank, means to prevent flow of the water to the air tank, and means to vary the capacity of the air tank and the amount of water received in the water tank to maintain certain relations between the volume of water in the water tank and the volume of air in the air tank.
11. In water supply means for concrete mixers, in combination, a water tank, a water line to supply water under pressure to said tank, means to limit the flow of water into the tank, and valve means to control passage of water to the tank from the supply line to compress the air previously in the tank so that said air will act as a motive fluid to thereafter expel the water from the tank, and also to control the outflow of the water from the tank, a mixing drum to which the water in the tank may flow when expelled therefrom, and a mixer loading skip adapted to actuate the said valve means to cause the water to pass from the water tank to the mixer before the skip discharges aggregates therein into the mixer.
12. In water supply means for concrete mixers, in combination, a water tank, a water line to supply water under pressure to said tank and to store up pressure, valve means to deliver the water from the tank to a mixer under said pressure, a mixer, a loading skip to charge solid aggregates into the mixer, and means adapted to coact with the valve means aforesaid to cause commencement of flow of water from the water tank to the mixer before the solid aggregates are charged into the mixer by the skip.
13. In water supply means for concrete mixers, in combination, a water tank, a water line to supply water under pressure to said tank, valve means to deliver the water from the tank to a mixer, a mixer, a loading skip to charge solid aggregates into the mixer, and means to build up a pressure head effective upon the water to subsequently cause commencement of flow of water from the water tank to the mixer before the solid aggregates are charged into the mixer by the skip and operable from the skip.
14. In water supply means for concrete mixers, in combination, a water tank, a water line to supply water under pressure to said tank and establish an air pressure head, valve means to deliver the water from the tank to a mixer, a mixer, a loading skip to charge solid aggregates into the mixer, and means operated by the skip for creating auxiliary air pressure on the water in the water tank to force the water therein therefrom.
15. In water supply means for concrete mixers, in combination, a water tank, a water line to supply water under pressure to said tank, valve means to deliver the water from the tank to a mixer, a mixer, a loading skip to charge solid aggregates into the mixer, and means operated by the skip for creating air pressure on the water in the water tank to force the water therein therefrom and consisting of an air inlet for the water tank, an air tank adapted to receive air from the water tank, valve control means for said air inlet, and skip actuated piston means in the air tank to compress air therein to act on the water in the water tank.
16. In water supply means for concrete mixers, in combination, a water tank, a water line to supply water under pressure to said tank, valve means to deliver the water from the tank to a mixer, a mixer, a compressed air tank to receive air from the water tank, and means to progressively compress the air in said tank to act on the water in the water tank to cause accelerated movement of water to the mixer.
17. In water supply means for concrete mixers, in combination, a water tank, a water line to supply water under pressure to said tank, valve means to deliver the water from the tank to a mixer, a mixer, a source of compressed air, and means under the control of the said valve means to cause the compressed air to act on the water as the valve means delivers the water to the mixer.
18. In water supply means for concrete mixers, in combination, a water tank, a water line to supply water under pressure to said tank, valve means to deliver the water from the tank to a mixer, a mixer, a source of compressed air, and means under the control of the said valve means to cause the compressed air to act on the water as the valve means delivers the water to the mixer, said valve means being operable to refill the tank with water after emptying thereof, and means to cause compression of air in the tank and replenish the source of compressed air supply as the tank is refilled.
19. The method of supplying water to concrete mixers which consists in establishing communication between a water tank, which is open to the atmosphere when empty, and a water supply line, causing flow of water from the supply line under pressure into the tank and simultaneously cutting off of the tank from the atmosphere to compress air previously entering the tank, to provide a motive fluid for expelling said water from the tank, opening the tank to an outflow passage whereby such motive fluid may act to positively force the water through the outflow passage, elevating the aggregate material in a skip to mixer charging position and utilizing the elevating motion of said skip to compress the trapped air.
20. The method of supplying water to concrete mixers which consists in establishing communication between a water tank, which is open to the atmosphere when empty, and

- a water supply line, causing flow of water from the supply line under pressure into the tank and simultaneously cutting off of the tank from the atmosphere to compress air 5 previously entering the tank, to provide a motive fluid for expelling said water from the tank, opening the tank to an outflow passage whereby such motive fluid may act to positively force the outflow passage, trapping 10 the air in a separate compartment and varying the capacity of said compartment to vary the effective expulsion pressure head.
21. The method of supplying water to concrete mixers which consists in introducing water into a tank under pressure and trapping 15 the air in said tank to create a minimum pressure head, further compressing

said trapped air from the mixer charging instrumentality to create a maximum pressure head and expelling the water into the 20 mixer under the pressure head so produced.

22. The method of supplying water to concrete mixers which consists in introducing water into a receptacle under pressure and trapping the air in said receptacle 25 to establish a minimum pressure head, expelling water from said tank into the mixer under the influence of said pressure head while maintaining pressure head above the minimum established by the water pressure. 30

In testimony whereof we affix our signatures.

ERICH H. LICHTENBERG,
GEORGE EVANS WEBB.
